UNITED STATES PATENT OFFICE.

JAMES L. BOYD AND LEO SAWALLIRCH, OF GLENDIVE, MONTANA.

LIGHT-REFLECTOR FOR ENGINE-CABS.

1,184,613.

Specification of Letters Patent. Patented May 23, 1916.

Application filed January 5, 1916. Serial No. 70,469.

To all whom it may concern:

Be it known that we, JAMES L. BOYD and LEO SAWALLIRCH, citizens of the United States, residing at Glendive, in the county 5 of Dawson, State of Montana, have invented certain new and useful Improvements in Light-Reflectors for Engine-Cabs; and we do hereby declare the following to be a full, clear, and exact description of the invention, 10 such as will enable others skilled in the art to which it appertains to make and use the same.

This invention relates to a light reflector for engine cabs.

At the present time it is the practice in engine cabs to drop a plurality of lights from the roof of the cab, so that the steam, air and steam heating gages and the water glass will be lighted so that they may be readily 15 observed at night. This is exceedingly inconvenient inasmuch as the disposition of the lights in this manner seriously interferes with the movement of the operator within the cab.

It is therefore an object of our invention to provide a device by means of which the light will be directed to these instruments but which will prevent the light from shining upon the front windows of the cab.

It is a further object of our invention to so construct the device that the angle of reflection may be varied.

With these and other objects in view, such as will appear as our description progresses, 25 our invention comprises the combination and arrangement of parts as set forth in and falling within the scope of the appended claims.

In the drawing: Figure 1 is a side elevation of our device; Fig. 2 is a front elevation thereof; Fig. 3 is a vertical longitudinal section view showing the lamp socket and the reflector on the back wall; Fig. 4 is a top plan view of the device showing 45 the adjustable brace; Fig. 5 is a horizontal sectional view through an engine cab showing the position of the device therein, and Fig. 6 is a vertical sectional view through the cab.

Referring to the drawing by reference characters wherein like parts are indicated by like characters throughout the several views: The form of the device illustrated includes a rear wall 1 which is substantially 55 rectangular in form and from which a pair of diverging wings 2 extend, which wings

also extend downwardly from the wall 1 and are made preferably of a flexible metal and which are highly polished upon their inner faces. Extending between the wings 20 2 adjacent the rear wall 1 are upper and lower webs 3 and 4, which webs are also joined to the rear wall. These webs terminate short of the free ends of the wings 25 however as illustrated in the drawing. The upper web 3 is provided with an electric lamp socket 5 which may be attached to a suitable source of current and in which a lamp may be placed, which lamp, when so placed, will be located, as illustrated in dotted lines in the drawing, between the webs 30 3 and 4 and the wings 2. The lower web 4 is provided with an opening 6 directly below the socket 5, which opening is provided for the purpose of receiving a gas or oil fixture 70 so that where it is not practical to use an electric lamp, a gas or oil lamp may be used. The wall 1 is provided with a keeper 7 in which a hook 8 is detachably engaged, which hook is formed on the back of a reflector 9, the reflector being so located that the electric, gas or oil lamps will be in direct alignment with the center thereof. This device is adapted to be secured to the back-board 10 of a cab so that the light will be reflected onto the gages and water glass which are mounted on the rear end of the boiler 11, as illustrated in Figs. 5 and 6 of the drawing.

In order that the angle of divergence of the wings 2 may be varied, we have provided a pair of telescopic braces 12 which are secured to the wings and to the back-board 10 of the cab, the parts of the braces being adjustable on each other and held in their adjusted positions by bolts 13, which 95 bolts pass through holes and slots in the members of the braces, as clearly illustrated in the drawing. By adjusting the wings by means of these braces, the light may be prevented from shining upon the front windows 100 of the cab and into the eyes of the engineer and fireman and directed to the gages entirely.

While we have illustrated and described a particular embodiment of our invention, it has merely been for the sake of convenience and we do not wish to be limited to that particular embodiment as it is obvious that numerous changes may be made within the scope of the appended claims.

What we claim is:

1. In a device of the class described, a

- wall having a reflector removably mounted thereon, a pair of flexible metallic wings extending outwardly and downwardly from said wall, webs extending between the wings, 5 one of said webs having a lamp socket thereon and the other of said webs having an opening for receiving a gas or oil lamp and telescopic braces secured to the wings.
2. The combination with the back-board 10 of a locomotive cab, of a light reflector including a rear wall, a pair of wings extending outwardly from the wall, said wings being made of flexible metal and diverging and means secured to the wings and to the 15 back-board to vary the angle of divergence of the wings.

3. In a device of the class described, a wall having a reflector thereon, a pair of flexible metallic wings extending outwardly and downwardly from said wall and arranged in 20 diverging relation to each other and telescopic braces secured to said wings and adapted to be secured to the back-board of an engine.

In testimony whereof, we affix our signatures, in the presence of two witnesses.

JAMES L. BOYD.
LEO SAWALLIRCH.
